UNITED STATES PATENT OFFICE.

HARRY GRANT KIMBALL, OF BRONXVILLE, NEW YORK, ASSIGNOR TO THE WHITIN MACHINE WORKS, OF WHITINSVILLE, MASSACHUSETTS, A CORPORATION OF MASSACHUSETTS.

SKEWER-MOUNTING.

1,137,983.

Specification of Letters Patent.

Patented May 4, 1915.

Application filed August 15, 1911, Serial No. 644,251. Renewed September 3, 1913. Serial No. 787,992.

To all whom it may concern:

Be it known that I, HARRY GRANT KIMBALL, a citizen of the United States, residing at Bronxville, Westchester county, New York, have invented the Improvements in Skewer-Mountings hereinafter set forth.

The invention referred to is an improved mounting for skewers in metallic spinning creels, and consists in a simple and cheaply produced device, adapted to be safely and securely confined in a perforation of the metallic creel rail and providing in a single structure a step-bearing for an upper skewer and a top-holding bearing for a lower skewer, the latter bearing being specially adapted to support the skewer with the least friction.

In the drawings which illustrate the invention, Figure 1 is a vertical transverse section of a metallic spinning frame creel to which the invention is applicable; Fig. 2 a side elevation of the improved mounting therefor and its locking ring; Fig. 3 a vertical section of the same in place in the creel; 25 and Fig. 4 is a top plan of the mounting.

In the two-story creel of Fig. 1, the creel rails 1 are adjustably supported on a series of uprights 2 above the main frame of the machine, and the roving bobbins 3 are set 30 on the skewers 4 which are supported, top and bottom, by the rails so that they may revolve freely under the gentle pull of the roving unwinding from the bobbins. It will be understood that the roving drawn off 35 from the bobbins from the supply for the spindles of the spinning machine, which do not appear in the drawing.

The improved mounting consists of a piece 40 of hard material capable of taking a high polish or glaze, such as crockery, porcelain or other fictile material, and is preferably molded in a single piece of substantially circular cross-section with a laterally projecting flange at or near one end thereof. The 45 mounting is shown by itself in Fig. 2 and the flange thereof is marked 5, being formed in this instance at the extreme upper end of head of the piece or block. The upper 50 surface of the piece or block is concaved or dished as shown at 6, and its lower portion is tubular with rounded edges, as indicated at 7 in Fig. 3. The margin of the head flange 5 is also beveled or rounded as shown in the drawings, and the whole is well glazed, especially on its upper surface 5 and the inter-

rior surface of the tubular part. The mounting as thus formed is adapted to be inserted in a perforation in the creel rail which is made slightly larger than the diameter of the porcelain so that contraction 60 of the metal or expansion of the porcelain will not cause the latter to crack or break, and a locking means is applied to the mounting on the side of the rail opposite to the head flange so that the mounting will be 65 confined in place in the rail by the flange on one side and the locking means on the other. The flange rests preferably on the upper margin of the perforation, forming the vertical support for the device and the locking 70 means consists in the present instance of a split-ring 8 adapted to be snapped into an annular groove 9 formed on the porcelain piece just beneath the head flange, as shown by Fig. 3. When confined in this position, 75 the base or foot 4^a of an upper skewer is adapted to be stepped on the highly glazed, dished surface 6 and the top 4^b of a lower skewer is adapted to be inserted in the depending tubular part 7, the two skewers being 80 thus supported in substantial alignment with each other. The interior of the tubular part 4^b is also highly glazed, as above stated, and forms a top-holder for the skewer which is superior to any means 85 heretofore suggested for this purpose, since the friction of the tip of the skewer thereon is thereby reduced to a minimum and the bobbin will therefore revolve uniformly under the slightest tension of the roving. Such 90 rotation will tend to polish the wooden skewer tip rather than to wear it away as in the case of other top holders, and thus improve the action with continued use. If the frictional resistance to the rotation of the 95 skewers is not constant the resulting variation in the tension of the roving will produce thin spots therein which will pass into the spun yarn and impair its uniformity.

Inasmuch as the structure above described 100 is practically as simple in form and as easily produced as the common form of porcelain pot-bearing or step piece, it will be observed that the advantages above pointed out can be obtained at substantially the same cost as the single step-pieces, and it will be understood, of course, that they may be used indifferently either as step-bearings or top-holder bearings alone, or as combined step and top holder bearings, 110

such as indicated in Fig. 3, according as they are used in the top and bottom or the middle rails of the creel. It will be further observed that the improved mountings are 5 easily placed in and removed from the rails without requiring special tools for this purpose or depending on friction to retain them in place against accidental displacement, this latter feature being of special importance 10 inasmuch as in metallic creels any bearing made of vitreous material is likely to crack or burst under the frictional pressure. The positive confining means included as a part of this invention is therefore an important feature.

I claim:

1. A skewer mounting for metallic creels comprising a one-piece body or block of 20 fictile material formed with a tubular lower portion adapted to receive a skewer tip and a dished upper surface forming a step-bearing, and provided with a laterally disposed supporting surface whereby it may rest without danger of rupture in a perforation 25 in the creel.

2. A skewer mounting for metallic creels comprising a piece of fictile material having an integral head flange whereby it is supported within a perforation extending 30 through a creel plate, and formed with an upper dished surface and a lower tubular portion adapted to support the tip of a skewer.

Copies of this patent may be obtained for five cents each, by addressing the "Commissioner of Patents, Washington, D. C."

3. A skewer mounting for metallic spinning creels comprising a member adapted to 35 be held in a perforation in the creel and having a laterally projecting supporting flange, a tubular part below the flange adapted to receive the top of a lower skewer and an upper surface formed as a step-bearing for the base of an upper skewer.

4. A skewer mounting for metallic creels composed of a block or piece of highly glazed, fictile material formed with a tubular lower portion adapted to receive the 40 tip of a skewer, and means which are not subject to expansile pressure against said piece for supporting the same in a perforation in a metallic creel rail.

5. A skewer mounting for metallic creels composed of step-bearing surface, a top-holding surface and a lateral flange surface, all combined in a single structure and adapted to be placed in a perforation in the metallic creel rail, combined with non-frictional means for confining such structure within its said perforation, whereby it is relieved of expansile pressure.

In testimony whereof, I have signed this specification in the presence of two witnesses.

HARRY GRANT KIMBALL.
